UNITED STATES PATENT OFFICE

168,440

AUTOMOTIVE VEHICLE DOOR

Buford E. Flatt, El Monte, Calif.

Application July 31, 1952, Serial No. 20,868

Term of patent 14 years

(Cl. D14—3)

To all whom it may concern:

Be it known that I, Buford E. Flatt, a citizen of the United States, residing in the city of El Monte, in the county of Los Angeles and State of California, have invented a new, original, and ornamental Design for an Automotive Vehicle Door, of which the following is a specification, reference being had to the accompanying drawing forming part thereof.

Fig. 1 is a front perspective view of an automotive vehicle door, showing my new design.

Fig. 2 is an interior perspective view thereof, the dotted line showing of the cab portion of a vehicle being for illustrative purposes only.

Fig. 3 is a perspective view showing the side of the interior of the door which is not shown in Fig. 2.

I claim:

The ornamental design for an automotive vehicle door, substantially as shown and described.
BUFORD E. FLATT.
